UNITED STATES PATENT OFFICE

158,630

GLARE SHADE OR SIMILAR ARTICLE

Wayne G. Williams and Joseph C. McGinnis,
Chicago, Ill.

Application May 6, 1949, Serial No. 2,492

Term of patent 14 years

(Cl. D57—1)

To all whom it may concern:

Be it known that we, Wayne G. Williams and Joseph C. McGinnis, citizens of the United States, residing at Chicago, in the county of Cook and State of Illinois, have invented a new, original, and ornamental Design for a Glare Shade or Similar Article, of which the following is a specification, reference being had to the accompanying drawing, forming a part thereof.

Figure 1 is a front perspective view of a glare shade or similar article, showing our new design;

Figure 2 is a top plan view thereof; and

Figure 3 is a front elevational view of the same.

We claim:

The ornamental design for a glare shade or similar article, as shown.

WAYNE G. WILLIAMS.
JOSEPH C. McGINNIS.
